UNITED STATES PATENT OFFICE.

GEORGE E. KIMBALL, OF CHICAGO, ILLINOIS, ASSIGNEE, BY MESNE ASSIGNMENTS, TO FIRST TRUST AND SAVINGS BANK, TRUSTEE, OF CHICAGO, ILLINOIS.

TELEPHONE BUSY-SIGNAL APPARATUS.

1,144,880.

Specification of Letters Patent. Patented June 22, 1915.

Application filed September 18, 1908. Serial No. 385,280.

To all whom it may concern:

Be it known that I, GEORGE E. KIMBALL, a citizen of the United States of America, and resident of Chicago, Cook county, Illinois, have invented a certain new and useful Improvement in Telephone Busy-Signal Apparatus, of which the following is a specification.

My invention relates to telephone systems in general, and contemplates an improved busy-signaling apparatus—that is to say, an improved apparatus for supplying the busy-signal current which is transmitted to a calling subscriber whenever the called line is busy.

Generally stated the object of my invention is the provision of an improved and highly efficient busy-signaling apparatus.

Special objects of my invention are the provision of a busy-signaling apparatus which is normally at rest; the provision of a busy-signaling apparatus having a buzzer or interrupter for producing the busy-signal current; the provision of a busy-signaling apparatus comprising only relays or electromagnets, together with suitable connections and coils and condensers; the provision of a polarized electro-magnet armature having means for intermittently interrupting the busy-signal current, so as to produce a busy-signal of the well-known and peculiar character; and the provision of certain details and features of improvement and combinations tending to increase the general efficiency and serviceability of an apparatus of this particular character, and adapted for use in various other connections.

To the foregoing and other useful ends, my invention consists in whatever there is of patentable novelty disclosed in the accompanying drawings and the following specification and claims.

In the said drawings, Figure 1 is a front elevation of a ringer to which is attached the circuit-breaker feature of my invention. Fig. 2 is a side view of the same. Fig. 3 is a rear view of the lower part, showing more clearly the circuit-breaker parts. Fig. 4 is a diagrammatic view showing the circuit connections embodying the principles of my invention. Fig. 5 is a detail view of the spring 8 shown in Figs. 1 and 2.

The circuit-breaking device comprises a shaft 8 rotatively mounted on the bracket 9, which latter is secured to the saddle piece

10 by the screws 11. The bracket and saddle piece thus assembled are securely clamped to the permanent magnet 12 of the ringer mechanism, as shown in Figs. 1 and 2. On the front end of the shaft 8 is secured by the set-screw 13 the toothed wheel 14 by means of which the shaft is rotated. To the rear end of said shaft is secured the circular bushing 15 (Fig. 3) having an elevation or lug 16 which, as the shaft is rotated, bears against the spring 17, carrying it out of engagement with the spring 18. The said springs are insulated from each other and from the bracket or support 19 upon which they are mounted. The bracket 19 is secured to the permanent magnet 12 by the clamp 20 and screws 21. To the ringer armature 22 is riveted at the point 23 a driving spring arm 24, which latter is suitably provided with a lateral extremity 25 for engaging the teeth of the wheel 14, and which extremity is normally retained in engagement therewith by the tension of the spring arm 24. Said armature is carried on and crosswise of a torsional spring 26, which latter is carried on the yoke 27. With this arrangement the armature 22 in vibrating, when the relay coils become energized, imparts a to-and-fro motion to the arm 24, which latter, when in its advanced position, engages a tooth of the wheel 14, and on the return stroke of the arm the end 25 rotates the engaging wheel. The said wheel is retained in its advanced position by the dog or pawl spring 26, which latter is secured to the shaft bracket 9.

The engagement of the springs 28 and 29 (Fig. 4), which may be caused in any suitable manner, closes an energizing circuit through the relay 27 which, upon energization, attracts its armature 28, thereby closing in contact the generator springs 29 and 30 and the battery springs 31 and 32. The engagement of the springs 29 and 30 closes an energizing circuit from the generator 5 to the relay coils. The mechanism then operates and imparts to the shaft 8 a rotative motion. The engagement of the springs 31 and 32 closes an energizing circuit through the buzzer relay 33, which latter then becomes energized and operates (in the well-known manner) the armature 34 that disengages the springs 35 and 36. The energizing circuit through the buzzer relay 33 extends from ground 37, springs 35 and 36, through the winding of the relay 33 to the 110

springs 31 and 32, battery lead 44, thence through battery b to ground g . Furthermore, the alternate make and break contact of the springs 35 and 36 causes the condenser 37 to alternately charge and discharge through the winding 38 of the induction-coil 39. The charging circuit, when the springs 35 and 36 are disengaged, extends from the battery b to the springs 32 and 31, through the winding of the relay 33, winding 38 of the induction-coil 39, condenser 37, resistance-coil 40, springs 17 and 18 to ground g^1 , thence to the grounded battery terminal g . Upon the engagement of the springs 35 and 36 the said condenser is discharged through the winding 38 of the induction-coil 39 to the buzzer relay springs 36 and 35 and to ground g^2 . As long as the relay 27 is energized the buzzer relay 33 continues to buzz and the condenser continues to be charged and discharged with each alternate opening and closing in contact of the springs 35 and 36, until the charging circuit is temporarily interrupted, when the shaft 8 rotates the bushing 15 and the lug 16 carries the spring 17 from engagement with the spring 18. Further rotation of the shaft carries the lug 16 from the spring 17, thereby permitting the springs 17 and 18 to again engage, reestablishing the energizing circuit of the condenser 37. Thus, during each revolution of the shaft 8 the charging circuit of the condenser is momentarily open while the projection 16 is in contact with the spring 17. The charging and discharging current of the condenser in passing through the winding 38, first in one direction and then in the other, induces in the secondary winding 41 of the induction-coil 39 a similar alternating current. From the conductors 42 and 43 this current may be taken for any suitable signaling purpose. As shown in Fig. 4, for example, suitable connections may be made with an automatic telephone system involving connectors of the type shown in United States Patent No. 815,176, granted March 13, 1906, to Keith, Erickson & Erickson. In Fig. 4 of the accompanying drawings, and in Fig. 51 of said patent, corresponding parts of the connector-switch to which the signaling current is taken have corresponding reference numerals, and the different parts will readily be recognized. Assume that a subscriber of an automatic exchange of the above mentioned type calls onto a busy line, and that the connector employed receives the busy release on the last rotary impulse; then when the subscriber presses his signaling button, instead of ringing the desired substation bell, the busy signal is received as follows: When the signaling button is pressed the vertical line conductor is grounded, which closes an energizing circuit through the vertical line relay of the connector. The latter relay closes an en-

ergizing circuit through the vertical magnet which operates in the well-known manner to raise the shaft B. The said shaft in rising carries the normal arm b^8 from engagement with the bushing of the spring b^{10} and allows the latter to come in contact with the spring b^{11} . This engagement closes an energizing circuit through the relay 27 (already explained) extending from ground g^3 through the relay winding 27 to the springs b^{11} and b^{10} , side switch wiper l^8 , ringer relay springs 7 and 6, through the winding of the back release relay M to the battery lead 44, thence through battery b to ground g . The relay 27 energizes and operates as previously explained. The charge and discharge of the condenser 37 through the primary winding 38 is discontinued for a short interval during each revolution of the bushing 15 when the projection 16 carries the spring 17 out of engagement with the spring 18, thus producing a buzz-buzz current in the secondary circuit of the induction-coil 39. From the conductor 42 of the winding 41 this current passes to the springs b^{11} and b^{10} , side switch wiper l^8 , ringer relay springs 7 and 6, condenser 4 to the conductor 2 of the calling line, through the secondary winding of the induction-coil and receiver of the calling substation to the conductor 1, through the winding of the vertical line relay O to the battery lead 44, springs 32 and 31 and to the conductor 43 of the secondary winding 41. The calling subscriber upon hearing the intermittent buzz in his receiver immediately recognizes the busy signal and understands that the desired substation is in service.

The relays and coils may be of any suitable resistance and it has been found that good results are obtained when the relay 27 is wound to a resistance of thirteen hundred ohms; buzzer relay 33 five hundred ohms; resistance-coil 40 five hundred ohms; winding 38 one-half ohm; and winding 41 fifty-six ohms.

From the foregoing it will be seen that I use a polarized electro-magnet armature for actuating the circuit-breaker by which the flow of busy-signal current is intermittently interrupted for the purpose of producing the characteristic or well-known form of busy-signal. Also, it will be seen that I employ an electric buzzer or interrupter for producing the busy-signal current, which current is afterward, as stated, interrupted intermittently and at a comparatively slow rate by the rotation of the shaft 8. Furthermore, it will be seen that no part of my improved busy-signaling apparatus is normally in motion—that is to say, the entire apparatus is normally at rest. The ringing generator 5 may, of course, be operated constantly, as is the usual practice in telephone exchange systems, but this generator is only the regular and usual ringing generator,

and although employed for furnishing the current for operating the shaft 8 really constitutes no part of the special busy-signaling apparatus. With this arrangement I find that good results are obtained in an economical and highly satisfactory manner. The polarized armature 22 and its operating electro-magnet X constitute, when employed in this manner, an alternating current motor for operating the switch or circuit-controller by which the busy-signal current is intermittently interrupted. It will be seen, of course, that different features and combinations of my invention are or may be found adapted for use in various connections.

What I claim as my invention is:—

1. In apparatus of the character set forth, the combination of means for producing a current of comparatively rapid variations, a switch for intermittently interrupting the current, a polarized armature connected for operating said switch, an electro-magnet for vibrating said armature, means for supplying alternating current of comparatively slower variations for energizing said electro-magnet, and means controlling the operation of said apparatus.
2. In apparatus of the character set forth, the combination of means for producing a current of comparatively rapid variations, a switch for intermittently interrupting the current, a torsional spring, a polarized armature mounted to vibrate against the torsion of said spring, means by which the said armature operates the said switch, an electro-magnet for vibrating said armature, means for supplying alternating current of comparatively slower variations for energizing said electro-magnet, and means controlling the operation of said apparatus.
3. In apparatus of the character set forth, the combination of means including a buzzer or interrupter normally at rest for supplying a signal current, means independent of said buzzer for intermittently interrupting said signaling current, and means controlling the operation of said apparatus.
4. In apparatus of the character set forth, the combination of means for producing a current of comparatively rapid variations, a switch for intermittently interrupting the current, an alternating current motor for operating said switch, means for supplying alternating current of comparatively slower variations to said motor, and electromagnetically-operated means for controlling the operation of said alternating current-supplying means.
5. In apparatus of the character set forth, the combination of a polarized armature, an electro-magnet for operating said armature, an electric circuit, a switch controlling said circuit, a rotary shaft for intermittently operating said switch, connections by which
6. In apparatus of the character set forth, the combination of an electric switch or circuit-controlling device, a ratchet device for intermittently operating said switch, a polarized armature for operating said ratchet device, an electro-magnet for operating said armature, means for supplying current to energize said electro-magnet, and electromagnetically-operated means for controlling the operation of said apparatus.
7. In apparatus of the character set forth, the combination of means including an electric buzzer or interrupter for producing a current, an energizing circuit for the electro-magnet of said buzzer or interrupter, a relay controlling said circuit, an energizing circuit for said relay, an automatic telephone switch, and means by which said relay circuit is closed by an off-normal condition of said automatic switch.
8. In apparatus of the character set forth, the combination of means including an electric buzzer or interrupter for producing a current, an energizing circuit for the electro-magnet of said buzzer or interrupter, a relay controlling said circuit, an energizing circuit for said relay, an automatic telephone switch, means by which said relay circuit is closed by an off-normal condition of said automatic switch, a switch for interrupting the current, a polarized armature, connections by which the armature operates the said switch for interrupting the current, a double-core electro-magnet for operating said armature, and an energizing circuit for said double-core magnet controlled by said relay.
9. In apparatus of the character set forth, the combination of means including an electric buzzer or interrupter for producing a current, an energizing circuit for the electro-magnet of said buzzer or interrupter, a relay controlling said circuit, an energizing circuit for said relay, an automatic telephone switch, means by which said relay circuit is closed by an off-normal condition of said automatic switch, a switch for interrupting the current, a polarized armature, connections by which the armature operates the said switch for interrupting the current, a double-core electro-magnet for operating said armature, an energizing circuit for said double-core magnet controlled by said relay, and a source of alternating current in the said circuit for energizing the double-core electro-magnet.
10. In apparatus of the character set forth, an induction coil, a condenser in circuit with the primary winding of said induction coil, a connection from said con-

denser to ground, a buzzer or an interrupter for alternately charging and discharging said condenser to thereby induce an alternating current in the secondary winding of 5 said induction coil, and means for intermittently interrupting said ground connection.

11. In apparatus of the character set forth, an induction coil, a buzzer or interrup-
10 ter for intermittently breaking the circuit through the primary winding of said induction coil, and means separate and apart from said interrupter or buzzer for intermittently breaking said circuit through
15 the primary at a second point.

12. In apparatus of the character set forth, an induction coil, a buzzer or interrup-
10 ter for intermittently breaking and making the circuit through the primary
20 winding of said induction coil to thereby

induce an alternating current in the secondary winding of said coil, a relay for controlling the operation of said interrupter or buzzer, and means for intermittently interrupting said current at a second point. 25

13. In apparatus of the character set forth, an induction coil, a condenser in series with the primary winding of said coil, an interrupter or buzzer for alternately charging and discharging said condenser to thereby induce an alternating current in the secondary winding of said coil, and a relay for controlling the operation of said interrupter or buzzer. 30

Signed by me at Chicago, Cook county, 35
Illinois, this 15th day of September, 1906.

GEORGE E. KIMBALL.
